UNITED STATES PATENT OFFICE.

WILLIAM T. MERSEREAU, OF ORANGE, NEW JERSEY.

DESIGN FOR METAL STAIR-PLATES.

Specification forming part of Design No. 7,574, dated July 21, 1874; application filed May 5, 1874.
[Term of Patent 7 years.]

CASE C.

To all whom it may concern:

Be it known that I, WILLIAM T. MERSEREAU, of Orange, Essex county, New Jersey, have invented and produced a new and original Design for Metal Stair-Plates, of which the following is a specification:

The nature of my design is fully shown in the accompanying photographic impression, to which reference is made.

The design consists of a row of the classic architectural ornaments known as "palmettes,"

having interposed between them ornate stanchions or cusps, the whole being surmounted by chevrons of zigzag scallop-work, all as represented.

What I claim as new is—
The design for metal stair-plates, as shown.

W. T. MERSEREAU.

In presence of—
A. SIDNEY DOANE,
E. E. BOND.
